ADAPTER BAR FOR OUTBOARD MOTORS

Harold L. Zimmerman, Box 606, Oshkosh, Wis.

Filed Mar. 14, 1962, Ser. No. 69,255

Term of patent 3½ years

(Cl. D71—1)

Fig. 1

Fig. 2

Fig. 3

The side not shown is a mirror image of the side shown in FIGURE 3.

I claim:

The ornamental design for an adapter bar for outboard motors, substantially as shown and described.
